[57] CLAIM

The ornamental design for a carrying case, substantially as shown and described.

DESCRIPTION

FIG. 1 is a top perspective view of a carrying case showing my new design;

FIG. 2 is a bottom perspective view thereof, but looking at the opposite side of that shown in FIG. 1;

FIG. 3 is a side elevational view thereof looking at the same side as shown in FIG. 2;

FIG. 4 is a top plan view looking in the direction of arrow 4 of FIG. 3;

FIG. 5 is an end elevational view looking in the direction of arrow 5 of FIG. 3; and

FIG. 6 is a bottom plan view looking in the direction of arrow 6 of FIG. 3.
